UNITED STATES PATENT OFFICE.

JOHN H. POOLE, OF JAMAICA, NEW YORK.

ICE-FORMING APPARATUS.

1,176,314.

Specification of Letters Patent. Patented Mar. 21, 1916.

Application filed March 13, 1915. Serial No. 14,211.

To all whom it may concern:

Be it known that I, JOHN H. POOLE, a citizen of the United States, residing at Jamaica, in the county of Queens and State of New York, have invented certain new and useful Improvements in Ice-Forming Apparatus, of which the following is a specification, reference being had to the accompanying drawings.

10 This invention comprehends certain new and useful improvements in apparatus for use in the artificial production of ice, and relates particularly to the manufacture of raw water, can ice.

15 To those familiar with the art to which this invention appertains, it is well known that the water in the freezing tank is agitated by means of air passing through a system of piping and issuing from tubes or 20 the like that extend down into the tank and the water contained therein. In the practice heretofore employed, a plurality of distributing pipes are used, the number and arrangement depending manifestly upon the

25 number of tanks and the arrangement of the latter, any desired number of laterals or branch pipes being connected to the distributing pipes and extending down into the tanks. Usually these branch pipes have been

30 made substantially in the form of yokes detachably connected to the distributing pipes at points where check-valves are provided, the branch pipes having metallic sections or extension members projecting down into the

35 water. At a predetermined point in the congealing of the water it has been customary to withdraw these branch pipes and their extensions, but from actual experience I have found that difficulties have been often

40 encountered, owing to the fact that the water had congealed to such a point that when the operators attempted to withdraw from the tanks the downwardly projecting metallic pipe sections, the joints between the 45 same and the main branch pipes or laterals have become detached, whereupon there have been left, within the blocks of ice, relatively long sections of pipes that have thus become irreparably lost. This one in-

50 stance alone has been found to be a very material factor in increasing the cost of the output, while at the same time the construction of these distributing pipes with their check valves mounted therein as well as the 55 construction and arrangement of the other

parts of the system above thus generally outlined, have tended to make the cost of maintenance and installation relatively high.

With a knowledge of these conditions my invention has for its primary object a simple, durable and efficient construction of parts, and arrangements thereof, whereby, in the first place, the cost of the output is materially reduced, owing to the fact that the branch pipes used to convey the air from the distributing pipes down into the tanks are provided with extension members formed of some frangible substance or material not detrimental to the ice and capable of being very cheaply made, so that the manufacturer can afford to leave these extension members or tubes in the ice by merely cutting them or breaking them off at a short distance above the upper surface of the ice block.

A further object of the invention is to provide means whereby the cost of installation and maintenance is reduced, owing to the fact that with my invention, the check valves above referred to are dispensed with, as will be hereinafter more fully described. 80 And the invention also aims to generally improve devices of this character so as to render them more useful and commercially desirable.

With these and other objects in view, as will more fully appear as the description proceeds, the invention consists in certain constructions, arrangements and combinations of the parts that I shall hereinafter more fully describe and claim.

For a full understanding of the invention, reference is to be had to the following description and accompanying drawing, in which

Figure 1 is a perspective view, in the nature of a diagram, illustrating the application of my invention, the branch pipe 3 being somewhat enlarged; Fig. 2 is a detail view illustrating two of the branch pipes in side elevation over portions of the tanks; Fig. 3 embodies two sectional views of one of the tanks, showing the different stages in the freezing of the ice; Fig. 4 is an enlarged sectional side elevation of one of the branch pipes and its downwardly projecting extension member, and Fig. 5 is a detail view showing the air-tight closure, which, when opened, will permit the insertion of the frangible extension member.

Corresponding and like parts are referred

110

to in the following description and designated in all of the views of the accompanying drawing by like reference characters.

Referring to the drawing, the numeral 1 5 designates some of the tanks of an ice plant manufacturing raw water can ice; 2 designates some of the main distributing pipes for the air which is derived from any suitable source of supply; and 3 designates my 10 improved branch pipes.

The distributing pipes 2 are, in the present embodiment of the invention, provided with a plurality of oppositely and laterally extending nipples 4, said nipples being preferably arranged in pairs, as shown, and there being one pair for every two tanks, 15 said nipples terminating in vertical planes short of the adjoining side walls of the tanks, whereby the latter may be readily removed whenever desired.

My improved branch pipes 3 are arranged for detachable connection to the nipples 4 of the distributing pipes 2, and in order to provide for the expeditious attachment and detachment of the branch pipes, they are in the present instance shown as provided at one end with clamping arms 5, arranged in diametrically opposite relation to each other and pivoted intermediate of their ends to 25 form handle portions 6, said clamping arms being spring pressed in closed position and their extremities being adapted to extend around and engage annular collars 7 formed on the extremities of the nipples 4. Preferably the branch pipes 3 carry washers 8 30 adapted to fit upon hollow bosses 9 and to abut against the outer faces of the nipples 4 when the pipes 3 are secured in their operative positions, whereby a tight joint will be 35 produced.

Operatively connected to the branch pipes 3 are extension members 10 in the form of pipes or tubes, these in the present embodiment of the inventive idea, being preferably 40 detachably connected to the downwardly projecting outer ends 3' of the pipes 3, the lower extremities 3'' of these downwardly turned ends, being preferably tapered, as best illustrated in Fig. 4. The 45 extension members 10 are formed with flared or bell-shaped upper ends 11 adapted to fit within the lower extremities 3'' just mentioned, whereby the pipes 3 and their extension members 10 will be operatively 50 connected together in a readily detachable manner.

In order to provide for the ready connection of the parts 3 and 10, openings are formed in the former at the juncture of the 60 main body portions thereof with the downwardly turned ends, and spring-pressed closures 12 normally cover said openings in an air-tight manner, whereby it is only necessary to move the closures to an open 65 position and insert the extension member 10

down through the openings when they will come to rest with the parts in their operative relation, illustrated best in Fig. 4.

From the foregoing description in connection with the accompanying drawing, the 70 operation of my improved ice manufacturing apparatus will be apparent. In the practical use of the device, after the tanks have been disposed in their proper positions, the branch pipes 3 and their extension members 75 10 are operatively placed, and whenever it is necessary to remove the pipes 3, all the operator has to do is to press together the handle portions of the clamping arms 5 to release them from the collars 7 of the 80 nipples 4. Then the branch pipes 3 (or, if desired, even before they are detached from the nipples 4,) can be readily separated from their extension members 10, the latter being left in the ice blocks, for said extension members are, as hereinbefore specified, composed of any suitable easily frangible non-metallic substance or material that can be cheaply made and not be detrimental to the quality of the ice. Usually, only about 85 90 three of the tanks are removed at the same time, and consequently the nipples thus opened may be permitted to "blow," for the amount of air thus wasted is practically negligible. Hence, no check valves are required, and this in itself tends to reduce the 95 cost of installation and maintenance.

It will thus be seen that I have provided a very simple and efficient construction and arrangement of parts whereby the tubes or 100 pipe extensions that extend down into the tanks or blocks of ice formed therein, may be left within the ice, as the cost thereof is very small and that my invention not only results in material economies in the cost of 105 the output of a plant of this character, but also simplifies the method of operation and reduces the cost of installation, as above stated.

While the accompanying drawing illustrates what I believe to be the preferred embodiment of my invention, it is to be understood that the invention is not limited thereto but that various changes may be made in the construction, arrangements and 115 proportions of the parts without departing from the scope of the invention as defined in the appended claims.

What is claimed, is:

1. In an ice forming apparatus of the 120 character described, an air distributing pipe and a branch therefor, the branch being provided with a downwardly projecting end having a tapered lower extremity, and a frangible extension member having a flared 125 upper end adapted to fit within said extremity, for the purpose specified.
2. In an ice forming apparatus of the 130 character described, an air distributing pipe, a branch therefor having a downwardly

projecting end with a tapered lower extremity, and an opening at the top of said end, an extension member of frangible material insertible through said opening into said end and formed with a flared upper end adapted to fit within said extremity, and a closure for said opening.

3. In an ice forming apparatus of the character described, a distributing pipe provided with a laterally projecting nipple, a branch pipe adapted to abut against said nipple, spring pressed clamping arms

adapted to detachably connect the branch pipe to said nipple, said branch pipe being formed with a downwardly extending end, 15 and a frangible extension member connected to said end, as and for the purpose set forth.

In testimony whereof I hereunto affix my signature in the presence of two witnesses.

JOHN H. POOLE.
